US00D748498S

(12) **United States Design Patent**
Pipes et al.

(10) **Patent No.:** **US D748,498 S**
(45) **Date of Patent:** **** Feb. 2, 2016**

(54) **PACKAGING TRAY**

(71) **Applicant:** **R.J. Reynolds Tobacco Company**,
Winston-Salem, NC (US)

(72) **Inventors:** **Jerry Wayne Pipes**, Clemmons, NC
(US); **Wesley Steven Jones**, Lexington,
NC (US); **Donald Leon Robertson**,
Stoneville, NC (US); **Steven A.
Hasselbach, Jr.**, Winterville, NC (US)

(73) **Assignee:** **R.J. Reynolds Tobacco Company**,
Winston-Salem, NC (US)

(**) **Term:** **14 Years**

(21) **Appl. No.:** **29/489,717**

(22) **Filed:** **May 2, 2014**

(51) **LOC (10) Cl.** **09-03**

(52) **U.S. Cl.**

USPC **D9/737; D9/456; D9/424**

CLAIM

The ornamental design for a packaging tray, as shown and described.

DESCRIPTION

FIG. 1 is a top, front perspective view of a packing tray;
FIG. 2 is a top, rear perspective view of the packaging tray;
FIG. 3 is a top plan view of the packaging tray;
FIG. 4 is an end view of the packaging tray;
FIG. 5 is an opposing end view of the packaging tray;
FIG. 6 is a front view of the packaging tray;
FIG. 7 is a rear view of the packaging tray;
FIG. 8 is a bottom, rear perspective view of the packaging tray;
FIG. 9 is a bottom, front perspective view of the packaging tray; and
FIG. 10 is a bottom plan view of the packaging tray.

1 Claim, 8 Drawing Sheets
